[57] **CLAIM**

The ornamental design for a fast food package, substantially as shown and described.

DESCRIPTION

FIG. 1 is a pictorial view of a fast food package embodying my new ornamental design.

FIG. 2 is a front elevational view of the package illustrated in FIG. 1.

FIG. 3 is a left end elevational view of the package illustrated in FIG. 1.

FIG. 4 is a rear elevational view of the package illustrated in FIG. 1.

FIG. 5 is a top view of the package illustrated in FIG. 1.

FIG. 6 is a bottom view of the package illustrated in FIG. 1; and,

FIG. 7 is a pictorial view of the package illustrated in FIG. 1 in an open alternate embodiment.

The right end elevational view is the mirror image of the right end elevational view as illustrated in FIG. 2.
